UNITED STATES PATENT OFFICE.

HARRY L. STERN AND JAMES G. CURRIE, OF PHILADELPHIA, PENNSYLVANIA, ASSIGNORS TO SIBSON & STERN, INC., OF PHILADELPHIA, PENNSYLVANIA, A CORPORATION OF PENNSYLVANIA.

DESIGN FOR LACE.

Application filed November 2, 1923. Serial No. 7,648. Term of patent 3½ years.

To all whom it may concern:

Be it known that we, HARRY L. STERN and JAMES G. CURRIE, citizens of the United States, and residents of Philadelphia, in the county of Philadelphia and State of Pennsylvania, have invented a new, original, and ornamental Design for Lace, of which the following is a specification, reference being

had to the accompanying drawing, forming part thereof.

The figure is an illustration of lace, showing our new design.

We claim:

The ornamental design for lace, as shown.
HARRY L. STERN.
JAMES G. CURRIE.
